BIRDPROOFING FOR STARLINGS AND SPARROWS

Julius Stanley Peles, New York, N. Y.

Application January 7, 1942, Serial No. 425,841

5 Claims. (Cl. 20—1)

This invention relates to birdproofing and has particular reference to such devices in relation to starlings and sparrows.

The birdproofing that has heretofore been known has been satisfactory principally for the larger birds such as pigeons, but has not been operative to suppress the nuisance of starlings and sparrows alighting on the ledges of buildings. In fact, these small birds frequently built their nests right in the pigeon proofing, which they often found facilitated the building of their nests. In certain localities, starlings and sparrows are a much worse nuisance than pigeons. Usually, at night, they revert again and again to the buildings they like to frequent. I have observed that they will obtain a grip on a thin wire, and succeed in standing thereon, a feat which pigeons cannot accomplish. Having once managed to alight on the birdproofing they proceed to find their way to a comfortable position on the ledge between the projects of the birdproofing.

Accordingly, starlings and sparrows have presented a problem which has long baffled the art, and the solution for which could not apparently be found by obvious expedients or by multiplying obstructions. Also it was necessary to bear in mind that the cost of the birdproofing must not become prohibitive. It was only after considerable study of the habits of starlings and sparrows, and experimentation with different kinds of birdproofing that I developed the present invention.

One object, therefore, of the invention is to provide birdproofing for starlings and sparrows which shall overcome the difficulties above mentioned.

Another object of the invention is the provision of such birdproofing which shall be relatively inexpensive to manufacture and adapted for quantity production.

Another object of the invention is to provide birdproofing for starlings and sparrows which shall not cause injury to pigeons attempting to alight.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary perspective isometric view showing a birdproofing element embodying the invention.

5 Fig. 2 is a plan view of a blank for forming the same.

Fig. 3 is an end view showing a modification.

Fig. 4 is a section on line 4—4 of Fig. 3.

Fig. 5 is a view in front elevation showing a 10 fragment of another modification.

Figs. 6, 7, 8 and 9 are fragmentary isometric perspective views showing different modifications according to the invention.

The advantages of the invention as here 15 outlined are best realized when all of its features and instrumentalities are combined in one and the same structure, but, useful devices may be produced embodying less than the whole.

It will be obvious to those skilled in the art 20 to which the invention appertains, that the same may be incorporated in several different constructions. The accompanying drawing, therefore, is submitted merely as showing the preferred exemplification of the invention.

25 Referring in detail to the drawing, 10 denotes birdproofing embodying the invention. The same consists of a one piece strip member of sheet metal which may be made to any desired length to extend along a ledge of a building that 30 is to be protected from starlings and sparrows. Preferably the structure 10 also possesses ample width so that it may be capable of covering the average ledge, but if the ledge be quite wide, two or more structures 10 may be placed side by side 35 thereon. The construction of the birdproofing 10 may be more readily understood by reference to Fig. 2. Here a blank in the form of a plane member 11 is formed with spaced cut outs 12 forming opposed free ended tongues 13, and intervening opposed members 14 which are integrally united at 15. Desirably the portions 13 and 14 are cut to taper toward the longitudinal center line of the member 11, the portions 15 being quite as narrow as practical for a purpose 40 later described. Now the member 11 is bent along a central longitudinal line which passes through the connecting portions 15 but is somewhat spaced from the points 16 of the elements 13. Obviously this bending is very easily effected, and it results in the provisions of two like sections 17 in the birdproofing 10, which sections may be formed with flanges 18 for securing to a ledge of the building. Thus each section comprises a 45 longitudinal base portion rigidly interconnecting its projections, the sections themselves being in-

terconnected solely at the portions 15. In completing the birdproofing 10, the free ended elements are bent outwardly as shown at 13a, whereas the members 14, due to the spacing between the sections 11, are downwardly divergent as shown at 14a. The portions 15 become generally like points as indicated at 15a.

It is thus seen that the birdproofing 10 comprises a plurality of sections, each having upwardly projecting portions terminating substantially in points, certain of the projections 13a being free ended at 16 and other intermediate projections 14a being integrally united at their point portions 15a. Also the projections 13a diverge upwardly while those at 15a converge upwardly. Thus a large number of projections are provided by a very simple, compact structure covering a large area.

Starlings and sparrows will be unable to alight on such birdproofing, because they will be hindered by the points 15a and 16, and because of the thin or relatively sharp longitudinal edges of said projections, and because the feet of the birds cannot obtain a satisfactory hold on the flat sheet metal of which the projections are formed. Thus the birds cannot encircle and grasp these projections, as they are relatively wide, except at their points. Hence these birds cannot alight on this birdproofing as they can on wires, however thin. Accordingly these birds will be unable to nest in this birdproofing.

Pigeons are also prevented from alighting, but if they should attempt to do so because their legs are longer than those of starlings and sparrows, they will not be injured by the points, because the height of the points above the bottom of the birdproofing is relatively small. Thus complaints from pigeon fanciers and others are avoided.

In Figs. 3 and 4 is shown a modification 18 such as to assure that even the smallest of starlings and sparrows will be unable to alight on the building. This structure is generally like that at 10, and may include sections 20 having free ended elements 21 and members 22 interconnected at their upper ends at 23. Formed integral with one of the sections 20 is a flange 24 having an integral member 25 having a series of upward extending points 26 lying parallel to the sections 20 and preferably centrally therebetween. These points 26 supplement the points of the projections 21, 22.

In Fig. 5 is shown a modified birdproofing 27, comprising a plane strip member of sheet metal having a base portion 28 formed with a securing flange 29 and having upward projecting portions 30 terminating in points 31. The projections 30 are flat and afford thin or sharp edges and are relatively wide except at their point portions to thus prevent sparrows and starlings from alighting as described for the birdproofing 10. It is of course understood that a plurality of these members 27 may be disposed in relatively close parallel relation to each other along a building ledge.

In Fig. 6 is shown a modified birdproofing 32 consisting of a one-piece strip member forming a base part 33 for securing to a ledge, and having upward extending projections 34 on opposite edges thereof, and being like the projections 30. To conserve material, these projections 34 are struck out longitudinally of the strip member, so that part of the base 33 are narrowed as at 35. To assure ample birdproofing coverage, the projections 34 are staggered or offset from each other lengthwise of the strip, and lie in planes

that may be parallel to each other and are transverse to the strip. The advantages and mode of operation stated for the birdproofing 10 will apply to that at 32.

5 In Fig. 7 is shown a modified birdproofing 36 consisting of a one-piece strip member forming a base plate 37 and having a multiplicity of spaced staggered integral points 38 and openings 39 formed incidentally to the cutting out of said tongues. A very large coverage is obtained by this birdproofing against starlings and sparrows, and thin or sharp edges 40 are formed on three sides of each projection, but the points are eliminated to avoid any injury to the birds. However, 10 the projections 38 may be pointed if desired. In other respects, the advantages of the birdproofing 36 are like those hereinbefore described.

15 In Fig. 8 is shown a modified birdproofing 41 having a base securing strip or plate 42 and a multiplicity of upward extending projections 43 thereto secured in any suitable manner, and being like those at 30 and 34, except that they lie in a variety of different vertical planes, and relatively close together.

20 In Fig. 9 is shown a modified birdproofing 44 comprising a plurality of upwardly projecting pointed elements 45 secured together in any suitable manner at 46 and at least one of them having a lateral anchor flange 47. The projections 45 are upwardly flared relatively to each other and when such devices 44 are used closely together they are highly effective against starlings and sparrows, because the elements 45 form relatively thin double edged wide tongues or blades, effectively pointed at their ends 48, these ends lying in an arc. The device 44 may also be used at corners and as a supplement to other birdproofing herein disclosed.

25 All the different forms of birdproofing have certain essential advantages of that in Fig. 1 and will keep off starlings and sparrows without injuring pigeons.

30 It is thus seen that I have provided birdproofing for starlings and sparrows which fulfills the objects of the invention and is well adapted for practical use, and inexpensive to manufacture and install.

I claim:

35 1. A device including birdproofing to prevent starlings and sparrows from alighting on the ledge of a building, including a one piece elongated member comprising upward projecting elements consisting of sheet metal and terminating in upwardly extending relatively pointed ends, said projections being relatively wide and having relatively thin edges longitudinally below said pointed ends, said projecting elements being disposed in a plurality of rows and being so closely spaced as to prevent said birds from alighting therebetween, each of said elements lying in a plane generally parallel to said rows, said birdproofing being of such height above the ledge that said pointed ends will not cause injury to pigeons attempting to alight on the ledge, and means for securing said projections to the ledge, said projections including free ended elements and members integrally united at their upper ends, and spaced base portions being provided uniting certain of said elements and members in a plurality of rows.

40 2. A device including birdproofing to prevent starlings and sparrows from alighting on the ledge of a building including a one piece elongated member comprising upward projecting elements consisting of sheet metal and terminating

in upwardly extending relatively pointed ends, said projections being relatively wide and having relatively thin edges longitudinally below said pointed ends, said projecting elements being disposed in a plurality of rows and being so closely spaced as to prevent said birds from alighting therebetween, each of said elements lying in a plane generally parallel to said rows, said birdproofing being of such height above the ledge that said pointed ends will not cause injury to pigeons attempting to alight on the ledge, and means for securing said projections to the ledge, said birdproofing being provided with parallel, separated base portions carrying said projecting elements, certain of the latter being united at their upper ends, one base portion having a flange carrying upward extending projections.

3. A device including birdproofing to prevent starlings and sparrows from alighting on the

ledge of a building, including a sheet metal strip longitudinally folded to provide a plurality of spaced sections each having free ended upward projecting elements and upward projecting members therebetween, adjacent members on said sections being united along the fold line of said strip, with the said strip thus having a plurality of spaced point like portions that constitute the junctions between said sections.

10 4. A device according to claim 3, wherein joined members are downwardly divergent and the members and elements of each section are upwardly divergent.

15 5. A device according to claim 3, wherein a flange is integrally connected to one of said sections to lie between the sections and is provided with upward extending projections lying between the sections.

JULIUS STANLEY PELES.
